Patented Oct. 26, 1915.

Inventor
De Lancey P. Harris
By his Attorney
Alfred Wilkinson

UNITED STATES PATENT OFFICE.

DE LANCEY P. HARRIS, OF NEW YORK, N. Y.

DESIGN FOR A TIRE-TREAD.

48,029.

Specification for Design.

Patented Oct. 26, 1915.

Application filed June 4, 1915. Serial No. 32,221. Term of patent 14 years.

To all whom it may concern:

Be it known that I, DE LANCEY P. HARRIS, a citizen of the United States, residing in New York city, county and State of New York, have invented a new, original, and ornamental Design for Tire-Treads, of which the following is a specification, reference be-

ing had to the accompanying drawing, forming a part thereof.

The figure is a plan view of a tire embodying my invention.

I claim,

The ornamental design for a tire tread.

DE LANCEY P. HARRIS.
